UNITED STATES PATENT OFFICE.

JOHN C. FRIEDRICH, OF BORDENTOWN, NEW JERSEY.

APPAREL.

SPECIFICATION forming part of Letters Patent No. 705,065, dated July 22, 1902.

Application filed August 24, 1900. Serial No. 27,935. (No model.)

To all whom it may concern:

Be it known that I, JOHN C. FRIEDRICH, of Bordentown, in the State of New Jersey, have invented certain new and useful Improvements in Apparel, whereof the following is a specification, reference being had to the accompanying drawings.

My invention is particularly adapted for embodiment in boys' shirt-waists; and it consists in providing such a garment upon its exterior with a circumferential series of buttons arranged to support a nether garment, which buttons are so secured upon the shirt-waist as to be removable and vertically adjustable above and below the normal waist-line thereof, as hereinafter described and claimed.

In the accompanying drawings, Figure 1 is a front elevation of a shirt-waist conveniently embodying my invention. Figs. 2 and 3 are respectively front and side views of a garment-support engaged with a waist-tab, as indicated in Fig. 1. Fig. 4 shows a modified form of garment-support engaged with a waist-tab. Fig. 5 is a perspective view of a garment-support of the form shown in Figs. 2 and 3.

Referring to Fig. 1, A is the waist-body, provided with plaits or equivalent reinforces. B represents vertically-pendent tabs arranged in a circumferential series upon the exterior of the waist-body, to which they are attached at their respective tops b in registry with respective plaits a, so that said tabs are supported by a reinforced portion of the garment extending to the top thereof. C represents garment-supports, each comprising a button c, having a clasp-frame c', to which a lever-clasp c² is pivoted at c³. As shown in Fig. 5, said lever-clasp c² is provided with serrations c⁴ at its inner edge. Said garment-supports C are arranged to be removably secured upon the tabs B in vertically-adjustable relation therewith, the frame c' being free for vertical adjustment when the clasp c² is turned in the position indicated in dotted lines in Fig. 3 and being fixed with respect to the tab when said clasp is turned into the position shown in full lines in said figure, in which latter position the serrations c⁴ are embedded in the tab.

Although I prefer to provide my improved

waist with the garment-supports C, above described, I do not desire to limit myself thereto, and I have shown in Fig. 4 a modified form 55 of garment-support C'. Said support C' comprises a button c⁵, having a U-shaped clasp-frame c⁶, and the vertical adjustment thereof is secured by the inclusion of a greater or less extent of the tab B within the clasp-frame c⁶.

Hitherto upper garments of the class described have been provided with a series of garment-supports secured at the waist-line in fixed relation with the waist-body, and in 65 order to fit persons of different height it has been necessary for the manufacturer to provide not only a series of circumferential sizes of waists, but also subseries of different lengths for each circumferential size. My 70 present improvement is advantageous in that a single series of different circumferential sizes of waists may be provided wherein variation in length from the shoulder to the waist-line of garment-supports may be secured by vertical adjustment of the latter. Moreover, as the material of which such garments are usually made is susceptible to shrinkage when the garments are laundered it is obvious that my improvements are 75 advantageous in that the purchaser may lower the waist-line of the garment in accordance with the shrinkage of the latter.

Although I prefer to provide my improved waist with buttons, it is to be understood that 80 any equivalent garment-support may be employed. For instance, the clasp-frame c' may carry a hook c⁷, as indicated in Fig. 3, which hook is adapted to engage a corresponding eye upon a skirt-band.

I do not desire to limit myself to the precise details of construction which I have shown and described, as it is obvious that various modifications may be made therein without departing from the spirit of my invention, and it is to be understood that the term "shirt-waist" used in the following claims is comprehensive of any similar garment.

I claim—

1. In a boy's shirt-waist, the combination with a series of vertically-pending tabs respectively fixed at their upper extremities upon the exterior of the garment; of rein-

forces *a*, in registry with said tabs, and extending vertically therefrom to the top of the garment; a button upon each of said tabs; and, means connecting said buttons with said tabs, adjustable from the top to the bottom of the latter, substantially as set forth.

2. In a boy's shirt-waist, the combination with a series of tabs of equal width throughout their length, respectively fixed at their upper extremities upon the exterior of the garment; of reinforces *a*, in registry with said tabs and extending vertically therefrom to the top of the garment; a series of clasps

frames *c'*, respectively embracing the width of said tabs and adjustable from end to end thereof; a series of buttons *c*, respectively fixed upon said clasp-frames *c'*; and, a series of clasps *c²*, respectively mounted in said clasp-frames and arranged to secure the latter in adjusted position upon said tabs, substantially as set forth.

JOHN C. FRIEDRICH.
